(No Model.)

C. F. GLOCKER.
OPERA GLASS.

No. 468,337.

Patented Feb. 9, 1892.

INVENTOR:

CARL F GLOCKER,
William N. Low,
ATTORNEY.

UNITED STATES PATENT OFFICE.

CARL F. GLOCKER, OF ALBANY, NEW YORK.

OPERA-GLASS.

SPECIFICATION forming part of Letters Patent No. 468,337, dated February 9, 1892.

Application filed January 27, 1891. Serial No. 379,304. (No model.)

To all whom it may concern:

Be it known that I, CARL F. GLOCKER, of the city and county of Albany, in the State of New York, have invented new and useful 5 Improvements in Opera-Glasses, of which the following is a specification.

My invention relates to an improvement in opera-glasses, which consists in providing means for rapidly adjusting the lenses to proper focal distances and in providing for 10 said glasses a convenient handle, which forms a suitable base for the mechanism whereby said adjustment is effected.

As commonly constructed the opera-glass 15 is an inconvenient article to hold for the purpose of viewing objects, and the adjustment of its lenses is effected quite slowly and frequently in a very unsatisfactory manner; and the object of my invention is to remedy said 20 defects. This object I attain by the means illustrated in the accompanying drawings, which are herein referred to and form part of this specification, and in which—

Figure 1 is a longitudinal section of one 25 form of my invention, showing the operating mechanism, the handle, and one part of the opera-glass in side elevation. Fig. 2 is a plan view of an opera-glass embodying the said 30 form of my invention. Fig. 3 is a side elevation of the handle and operating-lever detached from the opera-glass. Fig. 4 is a longitudinal section of a modified form of my 35 invention, with the handle, operating mechanism, and one part of the opera-glass shown in side elevation; and Fig. 5 is a horizontal section at the line X X of an opera-glass in which said modification is embodied.

As represented in the drawings, A designates the outer tubes of an opera-glass, the 40 same being of an old and well-known construction and connected together in the usual manner by a lower bar 1 and an upper bar 2, said tubes being provided with the usual object-glasses. The movable tubes B, connected 45 by a bar 3, are fitted to slide telescopically in the tubes A and are provided with the usual sight-lenses.

In the form of my invention shown in Figs. 1, 2, and 3, the bars 1 and 2 are connected 50 by a tube 4, which is rigidly secured to both of said bars, and the upper part of the tube 4 is provided with a longitudinal slot for a

purpose hereinafter explained. An opening is formed in the upper bar 2 to correspond with the bore of the tube 4, and into said 55 bore a tube or rod 5 is fitted to slide telescopically. The upper end of the tube 5 is secured to the bar 3, and a toothed rack 6 is secured to the last-named tube, so that the points of the teeth on said rack will protrude 60 through the slot in the tube 4, above referred to.

In the modification shown in Figs. 4 and 5 a tube 7 has its opposite ends journaled in the bars 1 and 2, so that said tube can be rotated on said journals. A pinion-gear 8 is secured to the tube 7, so as to be concentric to the latter. The bore of the tube 7 is provided with a screw-thread 9, of a quick pitch, and forms a nut which engages with a corresponding thread formed on a non-rotating screw 10, 70 which has its upper end secured in the bar 3, that connects the tubes B together. By rotating the tube 7 the screw 10 will be intrusively and protractively moved in said tube, the direction of said movements being dependent on the direction in which the tube 7 is rotated.

C designates the handle for the opera-glass, which is arranged at a right angle to an imaginary line between the centers of the 80 lenses. Said handle has a quadrant-gear 11 pivoted thereto, as at 12, said quadrant-gear being provided with an arm 13, having an eye 14 or other provision in which the user of the opera-glass can insert a finger of the hand 85 by which said glass is held for the purpose of imparting motion to said quadrant-gear. As shown in Figs. 1 and 2, said quadrant-gear is pivoted to the side of the handle C, so as to engage its teeth with those of the rack 90 6, and, as shown in Figs. 4 and 5, the quadrant-gear 11 is pivoted to the upper face of said handle, so that the teeth of said gear will engage with the teeth of the pinion-gear 8.

The handle C may be a permanent attachment to the opera-glass; but I preferably make it detachable therefrom, and to accomplish that purpose, as shown in Figs. 1 and 2, the tube 4 is provided with a socket 15, into which the end 16 of said handle is fitted to engage snugly, and, as shown in Figs. 4 and 5, pendent sockets or loops 17 are attached to the bar 2, and the extremity of the handle C is bifurcated to form prongs 18, which fit

snugly in said loops to retain said handle in required position in respect to the opera-glass. To render the handle C more convenient for carrying, I preferably make it with a joint, 5 as at 19, so that it can be folded at that point.

My invention is operated in the following manner: The handle C is held in the hand of the user, said handle being in an erect position to bring the opera-glass in a horizontal 10 position in correspondence to the eyes of the user, and one finger of the hand holding the opera-glass is inserted in the eye 14 of the quadrant-gear 11. Then by a slight movement of said finger the quadrant-gear may 15 be readily moved to effect an instantaneous adjustment of the lenses of the opera-glass to a focal distance that is suited to the eyes of the user.

I do not broadly claim the combination of 20 a lever pivoted to a handle and provided with a toothed segment and a toothed rack operated by said segment, as I am aware that such a construction, *per se*, is old and well-known; but

25 What I claim as my invention, and desire to secure by Letters Patent, is—

1. The combination, with an opera-glass composed of stationary tubes and movable tubes which slide telescopically and whose 30 movable tubes are connected, either directly or indirectly, to toothed gearing, of a handle for said glass, provided with a segment-gear which is pivoted to said handle and fitted to mesh into the gearing of said movable tubes, 35 said segment-gear having a lever fitted to be operated by a finger of the hand of the user, as and for the purpose herein specified.

2. The combination of the movable tubes of

an opera-glass provided with a toothed rack secured to the cross-bar between said tubes, 40 a handle attached to the immovable tubes, and a quadrant-gear pivoted on said handle and fitted to mesh into said rack, said segment-gear having a lever provided with an eye for receiving the finger of the user of the 45 opera-glass, as and for the purpose herein specified.

3. The combination of the immovable tubes of an opera-glass connected by cross-bars, a revoluble tube journaled on said cross-bars 50 and provided with an internal screw-thread, a pinion-gear secured to said revoluble tube, a handle attached to a fixed part of the opera-glass and having a quadrant-gear pivoted thereto, said quadrant-gear being fitted to 55 mesh into said pinion-gear, movable tubes fitted to slide telescopically in said immovable tubes and connected by a cross-bar, and a non-revoluble screw secured to the cross-bar of the movable tubes and fitted to engage in the screw-thread of the revoluble tube of the immovable tubes of the opera-glass, as and for the purpose herein specified.

4. The combination, with an opera-glass provided with toothed gearing for effecting 65 the adjustment of its lenses to a focal distance, of a handle connected to said opera-glass and having a quadrant-gear pivoted thereto, said quadrant-gear being fitted to engage in the toothed gearing of the opera-glass, 70 substantially as and for the purpose specified.

CARL F. GLOCKER.
